UNITED STATES PATENT OFFICE.

NELLIE WHELAN, OF PHILADELPHIA, PENNSYLVANIA.

HAIR-CRIMPER.

SPECIFICATION forming part of Letters Patent No. 618,630, dated January 31, 1899.

Application filed March 17, 1898. Serial No. 674,192. (No model.)

To all whom it may concern:

Be it known that I, NELLIE WHELAN, a citizen of the United States, residing in the city and county of Philadelphia, State of Pennsylvania, have invented a new and useful Improvement in Hair-Curlers, which improvement is fully set forth in the following specification and accompanying drawings.

My invention consists of an improved construction of hair-curler, the novel features of which will be hereinafter fully set forth, and particularly pointed out in the claim.

Figure 1 represents a side elevation of a hair-curler embodying my invention. Fig. 2 represents a perspective view showing the curler in operative position. Fig. 3 represents a sectional view on line xx , Fig. 1.

Similar letters of reference indicate corresponding parts in the figures.

Referring to the drawings, A designates a hair-curler, which consists of a frame or section of wire or other suitable flexible material B, which is inclosed within a casing or tube C, of leather, cloth, chamois, skin, or other analogous material, said casing being packed with cotton, wool, or any other soft substance C², whereby a thickened body portion is formed which is conical or tapering at one extremity C' thereof, the meeting edges of the casing being stitched or secured in any suitable manner.

The frame B is bent into a loop B' at one end D of the curler, said loop being inclosed within the casing C, which latter has an eye 35 or opening E in alinement with the loop B', said eye extending through said casing, which latter is slightly flattened at the end adjacent said eye.

I stitch or otherwise secure the walls of the eye as a buttonhole within the walls of the loop, so that said loop is entirely incased and thus prevented from displacement and its shape will be preserved, while the eye is re-

inforced and presents a yielding or soft surface for contact of the narrow end of the sack 45 therethrough, while concealing the metal interior.

The operation is as follows: The hair of the wearer is wound around the curler to the desired extent, after which the ends of the 50 curler are deflected toward each other, being bent at the points F. The tapered end C' is passed through the eye E, then passed under or around the body of the curler, and, if desired, in between the loop thus formed, as 55 shown at G, thus causing the curler to firmly engage the hair of the wearer.

It will be apparent that by inclosing the loop B' within the casing C in the manner described, when the end C' is passed through 60 the eye E there will be considerable frictional contact between the contiguous different portions of the casing C, whereby liability of the withdrawal of said end C' from said eye is reduced to a minimum, an advantage being 65 thus attained over other constructions in which the wire loop or eye is uncovered, so that the end of the curler can readily slip therethrough and become disengaged therefrom.

Having thus described my invention, what I claim as new, and desire to secure by Letters Patent, is—

A hair-curler consisting of an interior body formed of a shank of pliable material and a 75 loop at one end thereof, and an exterior tubular sack and packing therein, said sack being tapering at one end and having the other end widened and a stitched buttonhole therein, entirely inclosing said loop, the walls 80 of said eye being secured around the inner walls of said loop.

NELLIE WHELAN.
